OTHER PUBLICATIONSCE Smith Roller Style Boat Trailer Guide-On. <https://www.wholesalemarine.com/ce-smith-roller-style-boat-trailer-guide-on.html> Accessed Aug. 26, 2013.*Primary Examiner* — Cynthia M Chin(74) *Attorney, Agent, or Firm* — Robert C. Montgomery; Montgomery Patent & Design LP(57) **CLAIM**

The ornamental design for a pontoon boat loading guide, as shown and described.

DESCRIPTION

FIG. 1 is a top front side perspective view of a pontoon boat loading guide, showing my new design;

FIG. 2 is a bottom rear side perspective view thereof;

FIG. 3 is a front side elevation view with the back side elevation view being a mirror image thereof;

FIG. 4 is a left side elevation view with the right side elevation view being a mirror image thereof;

FIG. 5 is a top side plan view thereof; and,

FIG. 6 is a bottom side plan view thereof.

The broken lines represent portions of the article that form no part of the claim.
